DESIGN FOR A FOUNTAIN BAG OR THE LIKE

Frank Dabroski, Matawan, N. J.

Application September 3, 1937, Serial No. 71,447

Term of patent 14 years

To all whom it may concern:

Be it known that I, Frank Dabroski, a citizen of the United States and resident of Matawan, in the county of Monmouth and State of New Jersey, have invented a new, original, and ornamental Design for a Fountain Bag or the like, of which the following is a specification, reference being had to the accompanying drawing, forming part thereof.

Figure 1 is a front elevation of a fountain bag, showing my new design. Figure 2 is a side elevation of the same. Figure 3 is a cross section of Fig. 1 taken on the line x—x of Fig. 1.

I claim:

The ornamental design for a fountain bag or the like as shown.

FRANK DABROSKI.
